SWITCH BOX

Ernest G. Johansson, Watertown, Mass., assignor to The Palmer Electric & Manufacturing Co., Waltham, Mass., a corporation of Massachusetts

Original application August 19, 1931, Serial No. 558,038. Divided and this application January 4, 1933, Serial No. 650,115

8 Claims. (Cl. 200—77)

This application is divided from my copending application Serial No. 558,038, filed August 19, 1931. The invention relates to improvements in boxed electrical switches. When current-carrying circuits are made or broken by the throwing of a switch, it is desirable that the closing or opening movement of the make-and-break member be rapid, especially on the break, so as to minimize sparking at the terminals with resultant injury thereto. To this end a snap-action mechanism is provided by which movement of the make-and-break member of the switch is made against a resilient force up to a certain point, after which this force assists the movement of the member to the end of its stroke and causes rapid motion thereof. According to the invention the switch is housed in a box a portion of which is stiffly resilient and is employed in producing the snap-action. In the embodiment of the invention illustrated on the drawing and hereinafter described, a box having a bottom wall of sheet metal or other stiffly resilient material is employed. The operating mechanism for the make-and-break member of the switch is so arranged as to distort the bottom of the box during the early part of its stroke in either direction, the resilient force of the distorted box bottom acting to move the member through the remainder of its stroke. As the bottom of the box is stiff, the restoring force is considerable so that the remainder of the stroke of the make-and-break member is very rapid. The contact element on the make-and-break member is arranged with reference to the fixed contact or contacts which it engages so that the actual separation of the engaging contacts occurs during the rapid portion of the stroke of the make-and-break member.

The operating means for the make-and-break member may include a rock-shaft. In the embodiment of the invention hereinafter described, a rock-shaft is mounted parallel to the bottom of the box and is supplied with a cam member shaped to spring a portion of the shaft and a portion of the box bottom away from each other. In order to obtain a restoring force for the operation of the make-and-break member, the box bottom may be resilient, as hereinbefore set forth, or the rock-shaft may be resiliently yielding, or both the shaft and box bottom may yield.

For a more complete understanding of the invention, reference may be had to the description thereof which follows, and to the drawing, of which,—

Figure 1 is an elevation, partly broken away to

show in section, of a switch box and switch embodying the invention.

Figures 2 and 3 are partial views of the same, showing the parts in different positions of operation.

Figure 4 is a perspective view of the snap-action mechanism.

The switch and fuse-holding members may be housed in a suitable box 10 having a cover 11 hinged thereto. The box and cover may be made of stamped sheet metal as is customary in the art. For convenience in describing and claiming the apparatus illustrated, the box will be considered as lying with its back on a horizontal surface, the hinged cover thus forming the top 15 of the box. It is understood, however, that the box in actual use may be mounted in any desired position and is ordinarily fixed to a vertical wall. The bottom of the box is suitably pierced to receive screws 14 by which the box may be secured to a supporting wall 15, and is preferably offset from the supporting wall 15 by small bulges projecting outwardly as at 17 from the bottom of the box, preferably around the holes for the screws 14.

The fixed current-carrying elements within the 25 box are all mounted on a suitable unit block 25 which is preferably of molded porcelain or other suitable insulating material. The block is pierced vertically by a pair of holes 30 into which project portions of the switch elements, these holes 30 serving as cavities or pockets in which the current-rupturing separation of switch elements takes place so that the arcs are partially enclosed by the adjacent portions of the block 25. The holes 30 each include a pair of vertical grooves 31 35 which guide a sliding barrier 33 carrying a make-and-break or movable switch element 40 thereon.

The make-and-break member 40 is arranged to make contact with fixed terminal members 41 and 42 to close the switch when the barrier 33 is moved 40 upward. Suitable means for moving the barrier members 33 up and down are provided. As shown on the drawing, each barrier member is pierced near its lower end as at 34 to receive the reduced end of an arm 35. These arms are preferably made of insulating material such as vulcanized fiber and are mounted on a rock shaft 60. The rock shaft 60 as shown on the drawing is preferably made of flat bar stock of steel or other suitable material, and preferably has a bent portion 61 at one end acting as a crank arm with handle element 62. The arms 35 which operate the barrier members 33, are preferably slotted so as to fit loosely on the rock shaft. Since this slot in non-circular, the arms 35 rock with the 55

shaft 60. The shaft 60 may have a reduced portion 68 to bear in an aperture in a side wall of the box. As shown, an ear 65 is provided as a bearing for the end of the shaft remote from the handle, the ear 65 being secured to the bottom of the box.

For the more effective quenching of arcs between the bridging conductors 40 and the contact members 41 and 42, it is desirable that the 10 slides 33 be snapped or jerked downwardly when the conductors 40 are about to leave contact with the contact members in their circuit-breaking movement. A snap action device may be provided to produce automatically a short, quick 15 downward jerk on the plates 33 at the proper moment when the switch handle is swung to break the circuit. The snap action device illustrated on the drawing comprises a heart-shaped arm 70 of refractory material, this arm having a downwardly tapering portion below the shaft 60 terminating in a rounded lower end 73. The arm 70 is of such a length that in the lower portion of its swing with the rocking of the shaft 60 it engages the bottom of the box or an abutment element 15 thereon. If that portion of the bottom of the box is spaced from the supporting wall 15, it is free to give slightly. The shaft 60 may also be slightly resilient. As the end portion 73 of the arm 70 reaches the bottom of its swing, the shaft 30 60 and a portion of the bottom of the box are sprung away from each other by engagement of the arm 70 with the bottom of the box or an abutment thereon. As the end portion 73 passes the lowermost point of its swing, the powerful restoring 35 force arising from the stiffness of the shaft 60 and the bottom of the box presses strongly against one side edge or the other of the arm 70 and causes an exceedingly quick rotational movement of the shaft through a small angle. This 40 jerks the plates 33 up or down as the case may be. In the circuit breaking movement, the parts are so arranged that the jerk on the plates 33 comes just as the conductors 40 are leaving contact with the members 41 and 42.

45 The snap action may be produced by causing the end portion 73 of the arm 70 to engage directly against the inner face of the bottom of the box. As shown, however, an abutment member is mounted on the bottom of the box in the path 50 of the end portion 73. The abutment member is preferably made of wear resisting material such as hardened steel. While the abutment member may be made in various forms, it is shown on the drawing in the form of a hardened steel pin 74 which may be held loosely against the bottom of the box by a pair of loops 75 struck up from the bottom. This structure promotes a quick jerk which can be closely timed to occur at any desired 55 point of the stroke of the operating handle. The loose mounting of the pin 74 permits the pin to turn on its axis to present different portions of its periphery for engagement with the arm 70. This greatly prolongs the life of the abutment member.

60 It is evident that various modifications and changes may be made in the structure herein described and shown, without departing from the spirit or scope of the invention as defined in the following claims.

70 I claim:

1. Apparatus of the class described, comprising a box having a stiffly resilient wall portion, an electrical switch inside said box, means movable back and forth through a definite stroke for op-

erating said switch, said operating means having a stiffly resilient portion within the box and a handle outside the box, and means movable with said operating means to distort said resilient portions during a portion of each stroke whereby the restoring force of said resilient portions drives said operating means quickly through another portion of its stroke. 5

2. Apparatus of the class described, comprising a box, an electric switch mounted therein, and means for operating said switch, said means including a make-and-break element, a stiffly resilient shaft mounted in parallel spaced relationship to the bottom of the box and rockable to move said make-and-break element, and a snap action device having an abutment member on the bottom wall of said box and a rigid arm mounted to rock with said shaft and to engage said abutment member. 10

3. Apparatus of the class described, comprising a box having a bottom, an electric switch mounted within the box and having a make-and-break element, and means for operating said switch, said means including a shaft parallel to said bottom and rockable to move said make-and-break 25 element, and a spring snap action device including means for springing portions of said shaft and adjacent box bottom away from each other when the shaft is in a predetermined phase of its rocking motion. 30

4. Apparatus of the class described comprising a box, an electric switch mounted within the box and having a make-and-break element, and means for operating said switch, said means including a stiffly resilient shaft rockably mounted 35 in parallel spaced relation to a wall of the box and operably connected with said make-and-break element, and a spring snap action device having an arm mounted on said shaft to rock therewith and an abutment member mounted in the path of a portion of said arm. 40

5. Apparatus of the class described comprising a box having a stiffly resilient wall, an electric switch mounted therein, and means for operating said switch, said means having a spring snap 45 action device which includes said resilient wall of the box as an active element.

6. Apparatus of the class described, comprising an electric switch, a box containing said switch, said box having cooperating members consisting of the bottom wall thereof and a rockable shaft, one of said members being yieldable, means including said shaft actuatable to open and close said switch, and a snap-action device comprising a rigid arm on said shaft and rockable therewith and a wear-piece mounted in the box adjacent to said bottom wall and engageable by a portion of said arm in its rocking motion to spring said arm and box bottom away from each other. 50

7. Apparatus of the class described comprising a box adapted to be mounted on a wall, an electric switch mounted in said box, means projecting outwardly from the bottom of the box whereby a substantial portion of said bottom is spaced 55 from the surface of the wall on which it is mounted, switch-operating means including a shaft rockable to open and close the switch, and a snap action device comprising an arm mounted on said shaft to rock therewith and an element projecting inwardly from the bottom of the box into the path of a portion of said arm. 60

8. Apparatus of the class described, comprising an electric switch, a box containing said switch, said box having cooperating members consisting 70 75

of the bottom wall thereof and a rockable shaft, one of said members being yieldable, means including said shaft actuatable to open and close said switch, an arm mounted on said shaft and extending toward said wall, the end portion of said arm having converging cam edges, and a

cylindrical wear-piece rotatably mounted on said wall in the path of the end portion of said cam for yieldably moving said wall and shaft relative to each other.

ERNEST G. JOHANSSON. 5
